UNITED STATES PATENT OFFICE.

WILLIAM L. McGOWAN, OF SPICKARD, MISSOURI.

HOG-RINGER.

1,136,149.

Specification of Letters Patent. Patented Apr. 20, 1915.

Application filed August 20, 1914. Serial No. 857,636.

To all whom it may concern:

Be it known that I, WILLIAM L. McGOWAN, a citizen of the United States, residing at Spickard, in the county of Grundy and State of Missouri, have invented a new and useful Hog-Ringer; and I do hereby declare the following to be a full, clear, and exact description of the invention, such as will enable others skilled in the art to which it appertains to make and use the same.

This invention relates to an improved hog ringer.

As one of the objects of the invention it is the aim to provide an improved hog ringer having a magazine to contain a plurality of rings, whereby a number of hogs may be supplied with a ring one after another.

Another object of the invention is to provide a device with means whereby the parts may be adjusted, so that as each ring is fed between the jaws, it may be clenched, and constructed to fit a hog or shoat's nose, or even fit the nose of a small pig.

In practical fields the details of construction may necessitate alterations, falling within the scope of what is claimed.

The invention comprises further features and combination of parts, as hereinafter set forth, shown in the drawings and claimed.

In the drawings:—Figure 1 is a plan view of the improved hog ringer constructed in accordance with the invention, showing the jaws and handle members opened, with a ring between the jaws ready to be pressed together. Fig. 2 is a plan view of the hog ringer showing the opposite side of the same to that shown in Fig. 1, the ring having been pressed together. Fig. 3 is a longitudinal sectional view on line 3—3 of Fig. 1. Fig. 4 is a view in rear elevation of the hog ringer, more clearly showing the magazine. Fig. 5 is a side elevation of the improved hog ringer. Figs. 6 and 7 are detail views. Fig. 8 is a transverse sectional view through the ring magazine. Fig. 9 is an enlarged detail sectional view showing the hinged connections of the wings 9 of the ring guide 7.

Referring more especially to the drawings, 1 designates a casing, in which a slide 2 is mounted. The edge walls of the casing 1 are provided with slots 3. On one face of

the casing is a magazine 4, of a shape to receive a plurality of hog rings 6, that is, before they are pressed together. Arranged 55 in the magazine is a ring guide 7 comprising a central bar 8, to which the wings 9 are hinged at 10. These wings 9 act to guide the rings, as they pass from the magazine into the slide chamber, in advance of the 60 slide member 2. A plate 11 is arranged to engage the surfaces 12 of the wings, and the shank 13 (which is threaded) passes through an opening of the bar 8 and through the forward wall of the magazine, 65 there being a spring 14 on the shank, which acts to move the guide in one position, while the thumb nut or button 15 is used for moving the guide to another position. The magazine is provided with a cover 17, to 70 the under face of which, the arched plate 18 is secured, as shown. Passing through the cover and through the plate 18 is a rod 20 rectangular in cross section, which is provided with a bearing in the lower portion of 75 the magazine. The rectangular portion 21 of this rod 20 is at its upper portion, between the cover and the plate 18, while the remaining portion of the rod 20 is cylindrical, and slidable on the cylindrical portion 80 is a follower 22, which is provided with recesses or openings 23 which receive the wings 9 of the guide. This follower is disposed above the plurality of hog rings 6, and by the action of the spring 24 on the 85 rod 20 between the follower 22 and the plate 18, said hog rings are forced consecutively as they are used into the slide chamber in advance of the slide. In other words, the spring 24 and the follower acts as an automatic feed for said rings. Upon the rectangular portion 21 of said rod 20 is a plate 26 having a pair of compound curved dogs 27 pivoted to the ends of said plate 26. These dogs pass through openings in the sides of 90 the plate 18, and engage apertures 28 of the ends of the magazine adjacent its top portion, thereby locking the cover 17 in place, there being springs 29 connected to the plate 26 and the wall of the magazine, so as to 95 hold said dogs in said apertures. When it is desired to remove the cover 17, for filling the magazine, the rod 20 is partially rotated by grasping the knob 30. The slide 2 is 100

elongated and flat in contour and is provided with a pair of elongated slots 31 and 32. The slot 31 is provided with a narrow portion 33 and a broader portion 34. A coil spring is located or positioned in the narrow portion 33 of the slot 31, and has one end connected to a cross piece of the slide, as shown at 35, the other end of said spring is connected at 36 to said casing, said 10 spring acting to automatically move the slide forwardly, in order to discharge a hog ring from the slide chamber to and between the jaws 37. The end 38 of the elongated slide is provided with a threaded opening 39, in which a hollow or tubular exteriorly threaded screw 40 is threaded having a thumb flange 41.

Arranged in the hollow screw 40 is a bolt shank 42, there being a spring 43 interposed 20 between the head of the bolt 42 and the end of the screw 40, thereby acting to throw the bolt 42 toward the cross piece to which the spring 43 is connected at 35. A nut 44 is threaded to the bolt shank 42 beyond the 25 thumb flange 41 of the screw 40, so as to draw the bolt shank through the screw 40 against the action of said spring 43. The operating members or levers 45 and 46, are of the shape or contour in plan view as 30 shown in the drawings, and are duplicates in construction. Each operating member or lever is provided with forks 47 and 48, between which the casing 1 is received. The forks 47 of each member or lever are extended, as shown and terminate in the jaws 37, 35 which are provided with overhanging portions 49 and the beveled parts 50. A bolt 51 passes through the forks 47, through the casing 1, through the broad portion 34 of 40 the slot 31, and through the forks 48, and provided with a nut 52 for securing the parts together. In this manner the levers or members are pivotally mounted upon the casing 1. By pressing the handle ends 45 53 of the levers or members toward one another, the jaws 37 are brought together, in order to close the opposite portions of each hog ring, as it is discharged to and between the jaws. Pivoted at 54 to the head 55 of 50 the bolt shank 42 are links 56. One end of each link is provided with a slot 57 having a central narrow portion 58 and circular enlarged portions 59 and 60. The ends of the links 56 having said slots 57 are arranged 55 between the ears 61 of the handle ends of said levers or members. Passing through the ears 61, and through the slots 57 of the links 56 are thumb screws 62 having riveted or flared ends 63. The shank of each thumb 60 screw 62 is provided with a contracted neck 64. A coil spring 65 is interposed between the head of each thumb screw 62 and one of the ears of the handle end of each lever or member, thereby acting to hold the larger portion (adjacent the riveted or flared end

63) of the shank of each thumb screw, in one or the other of the circular enlarged opening or portions of the slot 57 of each link 56. This construction is for the purpose of adjustably connecting the handle 70 end of each lever or member 45 and 46 to each link. In other words, for adjusting each handle end of each lever or member 45 and 46 closer or farther apart relative to the elongated slotted slide, so as to increase 75 or decrease the opening and closing of the handle ends as well as said jaws. By adjusting the thumb nut 44 so as to move the bolt shank 42 to different positions than that shown, and by adjusting the screw 40, 80 the throw or movement of the handle ends of said levers or members 45 and 46 may be changed, so as to increase and decrease the opening or separating, and closing of said jaws, so as to shape or close different sizes 85 of hog rings. By pressing the thumb screws 62 against the action of their springs 65, the contracted necks of the shanks of the thumb screws may be arranged so as to be received in the narrow portions 58 of said slots 57, 90 that is, when arranging the larger cylindrical portions of the shanks of the thumb screw 62 in either of said larger portions 59 and 60 of said slots 57. By adjusting said rings relative to the handle ends of said levers 45 and 46, said levers may be adjusted in their relative movements, in closing different sizes of hog rings. A guide 67 for the jaw portions of said levers is provided, being secured at 68 to the casing 1. Members 100 69 are mounted in the slots 3 of the casing, to cooperate with the slide when discharging different sizes of hog rings.

From the foregoing it will be noted there has been devised an improved novel construction of hog ringer, and one in which plurality of rings may be fed consecutively to and between the jaws so as to be clenched, and one in which the parts are adjustable, whereby hog rings of different dimensions 110 may be clenched. This form of hog ringer has been found practical, efficient, and desirable upon farms and the like for the purpose intended.

The invention having been set forth, what 115 is claimed as new and useful is:—

In a hog ringer as set forth, a casing having a ring chamber, a slide plunger operable therein, a magazine for a plurality of hog rings, a pair of lever members pivoted to the 120 casing and having jaws beyond the ring discharge end of the casing, whereby a ring may be clenched as the lever members are manually forced together, and means in the magazine for feeding a ring into the ring 125 chamber as the slide plunger is receded or retracted when the lever members are operated toward one another, yieldable connections between said lever members and the slide member for retracting the same as the 130

lever members are operated toward each other, and means for automatically separating said lever members and their jaws, said last named means acting automatically to force the slide member through the ring chamber to feed a hog ring to and between said jaws.

In testimony whereof I have signed my name to this specification in the presence of two subscribing witnesses.

WILLIAM L. McGOWAN.
